UNITED STATES PATENT OFFICE.

ROY E. ANKERMAN, OF WAPAKONETA, OHIO.

AUTO JACK.

Application filed April 9, 1921. Serial No. 459,861.

To all whom it may concern:

Be it known that ROY E. ANKERMAN, a citizen of the United States of America, residing at Wapakoneta, in the county of 5 Auglaize and State of Ohio, has invented new and useful Improvements in Auto Jacks, of which the following is a specification.

The object of the invention is to provide 10 a simple and efficient equal acting jack for use in connection with automobiles and similar vehicles and in like capacities for raising and sustaining objects of considerable weight; and with this object in view the invention consists in a construction and combination of parts of which a preferred embodiment is shown in the accompanying drawings, wherein:

Figure 1 is a side view of a jack embodying the invention.

Figure 2 is a vertical sectional view of the same.

Figure 3 is a front view.

Figure 4 is a perspective detail view showing the operating lever;

Figure 5 is a similar view of the plunger bar;

Figure 6 is a similar view of one of the links connecting the operating lever with 30 the plunger bar;

Figure 7 is a perspective detail of the retaining pawl and operating lever.

The apparatus embodies a standard 10 of looped form consisting of a plate or bar doubled upon itself to form parallel sides 10^a which are secured at their lower extremities to a base 11 and are spaced apart to form an intervening slot for the operation of a plunger bar 12 extending slidably 35 through a guide opening 13 in the upper closed end of the standard and provided at its extremity with a saddle 14 for engagement with an auto axle or the like.

The operating lever 15 is provided with 45 a fulcrum pin 16 adapted for selective engagement with transversely registering seats 17 consisting of notches in the edges of the side members of the standard, the inner end of the lever which is preferably bifurcated 50 as shown at 18 to substantially span the space between the side members of the standard being connected by links 18^a with the lower end of the plunger bar. The bifurcation of the inner end of the lever serves

to ensure the lateral guiding movement of 55 the lower end of the plunger bar by holding the links substantially in contact with the inner surfaces of said members.

The lower end of the plunger bar is provided with a transverse guide pin 19 operating terminally in contact with the rear edges 60 of the side members of the standard, the said plunger bar near its lower extremity being deflected rearwardly to properly position said guide pin, while rearward displacement of the lower end of the plunger bar 65 through the operation of the lever is prevented by a guide pin 20 transversely spanning the interval between the side members 70 of the standard in rear of said plunger bar.

In connection with the above described mechanism there is employed a dog for engaging and holding the plunger bar in its step by step upward movement so as to sustain the load at the desired elevation and 75 permit of the shifting of the fulcrum pin of the lever from one seat in the standard to the next as the load is progressively elevated.

In the construction illustrated the dog 21 is pivoted upon the standard near its 80 upper end by means of a pin 22 transversely spanning the interval between the members of the standard and extended to form a crank 23 by which the dog may be disengaged from the plunger bar, the latter having a series of sockets 24 for successive engagement by a reduced nose portion 25 of the dog which is yieldingly held by gravity in position to engage said sockets as the plunger bar is advanced in raising the load 85 90 supported thereby.

A terminal extension 26 of the guide pin 20 is arranged in the path of swinging movement of the crank arm 23 to prevent the pawl from being thrown backward far 95 enough to be beyond the actuating effect of gravity tending to hold the dog in its operative or engaging position.

Having described the invention, what is 100 claimed as new and useful is:—

A jack having a standard consisting of laterally spaced side members provided in their front edges with series of transversely registering seats, a plunger bar guided for vertical sliding movement at the upper end 105 of the standard, a lever having a transverse fulcrum pin for selective engagement with said seats and having a permanent link

connection at its inner end with the lower end of the plunger bar, and a dog for locking the plunger bar in its step by step upward movement, the plunger bar being provided at its lower end with a transverse guiding pin for traversing the rear edges of the side members of the standard and a

guide pin arranged in spanning relation with said side members to limit the rearward swinging movement of said plunger bar. ¹⁰

In testimony whereof he affixes his signature.

ROY E. ANKERMAN.
